Patented Dec. 18, 1923.

UNITED STATES PATENT OFFICE.

ANDREW S. MACDOWELL, OF ROCHESTER, NEW YORK.

TYPEWRITER COPYHOLDER.

Application filed May 24, 1921. Serial No. 472,217.

To all whom it may concern:

Be it known that I, ANDREW S. MACDOWELL, a citizen of the United States of America, residing at Rochester, in the county of 5 Monroe and State of New York, have invented certain new and useful Improvements in Typewriter Copyholders, of which the following is a specification.

My invention relates to typewriter copy-holders, and is in the nature of a modification of the construction illustrated in my application Serial Number 369,431, filed March 27, 1920.

A principal object of the invention is to 15 provide an arrangement that permits the use of a continuously running operating motor, with instrumentalities controlled manually for connecting the operating motor with the movable part of the copyholder at will.

Still a further object of the improvement 20 is to afford mechanism that can be readily operated so as to actuate the movable element of the copyholder in either direction of its travel and at variable speeds if desired.

Still a further object of my invention is 25 to afford an economical and effective arrangement for operating the movable element, or copy supporting member, the same consisting of a vertically disposed rotary screw which is operatively connected with 30 the movable element so as to elevate or lower it, according to the direction of rotation of the screw.

The invention also comprehends certain 35 other improved features and advantages, all of which will appear clearly from the following description, in conjunction with the accompanying drawings, the novel features being pointed out in the claims following 40 the description.

In the drawings:

Figure 1 is a plan view showing the application of the invention to a conventional form of typewriter.

Figure 2 is a rear elevation of the copyholder.

Figure 3 is a sectional view on line 3-3 of Figure 2, with the flexible shaft removed.

Figure 4 is a side elevation of the motor 50 and controlling mechanism.

Figure 5 is an end elevation of the same.

Figure 6 is a view similar to Figure 4, with one pair of clutch members in engagement with each other.

Figure 7 is a sectional view on line 7-7 of Figure 2.

Figure 8 is a sectional view on line 8-8 of Figure 2, and

Figure 9 is a sectional view on line 9-9 of Figure 7.

The invention may be applied to different types of copyholders, and for convenience of illustration, and with the sole purpose of showing a practical example of various possible forms, I have illustrated the type of 65 copyholder which embodies a stationary frame or support on which is arranged to travel a vertically movable copy supporting member or platen which is disposed and travels preferably in a vertical plane.

In the construction illustrated, referring to Figure 2, A designates the stationary frame or support embodying vertical guide rods a, and B is the copy supporting member, which in the present instance constitutes the driven element that is movable in a vertical plane although it will be obvious to those skilled in the art that the driven element need not necessarily support the copy and also, may travel in some other direction than in a vertical plane.

Arranged at the top of the frame A is a bearing b, and arranged at the bottom of said frame on a lateral support c is a bearing d. Between said bearings b and c is disposed the vertical worm or screw C which is rotated in a manner that will be described presently. The screw C is operatively associated with the movable element B by means of a nut D that is carried 80 by the copy supporting member B and travels therewith upwardly and downwardly on said screw as the latter is operated in one direction or the other.

The screw C is provided at its lower extremity with a flat sided end portion e and an annular recess f, while g is a socket carried by the flexible shaft E and cooperating with said flat sided end e. The socket g is provided with an annular flange or rib h which 90 engages said recess f, thus affording a convenient detachable and interlocking connection between the flexible shaft E and the screw C. The flexible shaft E is rotated in either direction, and at variable speeds if desired, by the mechanism that will now be set forth in detail.

The copyholder is arranged usually in the rear of the typewriter as shown in Figure 1, while the controlling mechanism is preferably positioned in juxtaposition to the typewriter keyboard and this disposition

of the parts is permitted by the flexible shaft E which leads from the controlling mechanism to the copyholder, as indicated by Figure 1. Referring to Figure 4, F designates an electric motor arranged beneath the typewriter table G, and H is the motor shaft or driving element which is journaled at its outer end in bearing H' and has fixed thereon the clutch members I, I', preferably in the form of friction disks. The flexible shaft extends to a point between said friction disks I, I', and has fixed thereon a clutch member preferably in the form of a friction disk J, arranged to engage selectively the disks I and I'. To accomplish this, a flexible shaft E, see Figure 5, is journaled in a bearing K carried by a pivoted bracket L, said bracket being provided with a controlling handle M which extends through an opening in the typewriter table and is readily accessible to the operator. A spring N acts to retain the flexible shaft and the friction element J in neutral position as shown in Figure 4. When the handle M is thrown to the right to engage disks J and I, as shown in Figure 6, the flexible shaft and the copy supporting member are operated in one direction, and when the handle M is thrown to the left to engage disks J and I', said parts will be operated in the opposite direction. In some cases it may be desired to vary the speed of travel of the copy supporting member, and this is accomplished by shifting the friction disk J radially with reference to the centers of the friction disks I, I', thereby changing the gear ratio, as will be seen in Figure 5.

To this end, the spindle O, on which the handle M is mounted, is slidable in bearings P and P', being retained in normal position as illustrated in Figure 5 by the springs Q and Q'. To effect a change of speed of the copy supporting member, for operating it faster or slower in either direction, the handle M is first shifted forwardly or rearwardly of the typewriter table, referring to Figure 1, thereby causing a longitudinal shifting of the spindle O, before turning the handle to the right or left. When the desired adjustment of the friction disk J is obtained to give the proper rate of travel, which will be determined by the operator through practice, the handle M is shifted to the right or left, bringing the friction disk J into engagement with the selected disk I or I', and causing a rotation of the flexible shaft and upward or downward travel of the copy supporting member as the case may be.

While I have described the invention with more particular reference to a specific embodiment, it may be modified in various ways, and this application is intended to cover any changes or departures coming within the scope of my improvement or of the following claims.

I claim:

1. In a typewriter copyholder, the combination with a copy supporting member movable vertically and adapted to support copy in a vertical plane, of means for operating the copy supporting member comprising a driven element, a continuously moving driving element, and manually controlled means for operatively connecting the driven element with said continuously running driving element at will. 75

2. In a typewriter copyholder, the combination with a copy supporting member movable vertically and adapted to support copy in a vertical plane, of means for operating the copy supporting member comprising a driven element, a continuously moving driving element, and manually controlled means for operatively connecting the driven element with said continuously running driving element at will, said last mentioned means including devices whereby the driven element may be operated at variable speeds while the driving element operates at a constant speed. 85

3. In a typewriter copyholder, the combination with a copy supporting member movable vertically and adapted to support copy in a vertical plane, of means for operating the copy supporting member comprising a driven element, a continuously moving driving element, and manually controlled means for operatively connecting the driven element with said continuously running driving element at will, said last mentioned means including devices whereby the driven element can be operated in either of two directions while the driving element travels continuously in one direction. 95

4. In a typewriter copyholder, the combination with a copy supporting member movable vertically and adapted to support copy in a vertical plane, of means for operating the copy supporting member comprising a driven element, a driving element moving continuously in one direction, and manually controlled means for operatively connecting the driving and driven elements so as to operate the latter at variable speeds and in either of two directions. 105

5. In a typewriter copyholder, the combination with a copy supporting member movable vertically and adapted to support copy in a vertical plane, of means for operating the copy supporting member comprising a continuously moving driving element, and manually controlled means for operatively connecting said first mentioned element with said continuously running driving element at will. 115

6. In a typewriter copyholder, the combination with a copy supporting member movable vertically and adapted to support copy in a vertical plane, of means for operating the copy supporting member comprising a 120

- continuously moving driving element, and manually controlled means for operatively connecting said first mentioned element with said continuously running driving element at will, the vertically movable element being operable at variable speeds while the driving element operates at a constant speed.
7. In a typewriter copyholder, the combination with a copy supporting member movable vertically and adapted to support copy in a vertical plane, of means for operating the copy supporting member comprising a continuously moving driving element, and manually controlled means for operatively connecting said first mentioned element with said continuously running driving element at will, the vertically movable element being operable either upwardly or downwardly while the driving element travels continuously in one direction.
8. In a typewriter copyholder, the combination with a copy supporting member movable vertically and adapted to support copy in a vertical plane, of means for operating the copy supporting member comprising a driving element moving continuously in one direction, and manually controlled means for operatively connecting the driving element and the vertically moving element so as to operate the latter at variable speeds and in either of two directions.
9. In a typewriter copyholder, the combination with a copy supporting member movable vertically and adapted to support copy in a vertical plane, of means for operating the copy supporting member comprising a continuously moving driving shaft, a pair of clutch members fixed on the shaft, a driven shaft operatively connected with the vertically movable element, and a clutch member carried by the driven shaft and movable into engagement with either of the first mentioned clutch members.
10. In a typewriter copyholder, the combination with a copy supporting member movable vertically and adapted to support copy in a vertical plane, of means for operating the copy supporting member comprising a continuously moving driving shaft, a pair of clutch members fixed on the shaft, a flexible driven shaft operatively connected with the vertically movable element, and a clutch member fixed on said flexible shaft, the flexible shaft and its clutch member being movable selectively into engagement with the first mentioned clutch members.
11. In a typewriter copyholder, the combination with a copy supporting member that is movable in a vertical plane for exposing lines of copy successively, of a vertically disposed screw operatively associated with the copy supporting member for elevating and lowering it, and operating means connected with said screw.
12. In a typewriter copyholder, the combination with a copy supporting member that is movable in a vertical plane for exposing lines of copy successively, a vertically disposed rotary screw, a nut carried by the copy supporting member and engaging the screw, and operating means connected with the screw for turning it in either direction.
13. In a typewriter copyholder, the combination with a copy supporting member that is movable in a vertical plane for exposing lines of copy successively, of a vertically disposed screw operatively associated with the copy supporting member, a continuously moving driving element, and manually controlled means for operatively connecting the driving element with said screw at will and driving the screw in either direction.
14. In a typewriter copyholder, the combination with a copy supporting member that is movable in a vertical plane for exposing lines of copy successively, of a rotary vertically disposed screw operatively associated with the copy supporting member, and a flexible shaft detachably connected with the screw for turning the latter.
15. In a typewriter copyholder, the combination with a copy supporting member that is movable in a vertical plane for exposing lines of copy successively, of a vertically disposed rotary screw operatively associated with the copy supporting member and acting to raise or lower the same, a flexible shaft detachably connected with said screw, a driving shaft, a pair of clutch members fixed on the driving shaft, and a clutch member fixed on said flexible shaft and arranged between the first mentioned clutch members, said flexible shaft being bodily movable to bring its clutch member into engagement selectively with the clutch members on the driving shaft and at different radial positions relatively thereto so as to operate at varying speeds and in either direction.
16. In a typewriter copyholder, the combination with a copy supporting member movable in a vertical plane for exposing lines of copy successively, of a rotary vertically disposed screw operatively associated with the copy supporting member, a continuously moving driving element, and manually controlled means for operatively connecting the driving element with said screw at will.

In witness whereof, I have hereunto signed my name.

ANDREW S. MacDOWELL.
